(57) **CLAIM**

The ornamental design for a pilsner container, as shown and described.

DESCRIPTION

FIG. 1 shows a perspective view of a pilsner container of the invention, including both a base and the beverage holder in their combined orientation;

FIG. 2 shows a perspective view of a pilsner container of the invention, this time with the base and the holder separated;

FIG. 3 shows a side view of a pilsner container of the invention;

FIG. 4 shows a side view of a pilsner container of the invention, with the beverage holder and base separated;

FIG. 5 shows a top view of a pilsner container of the invention;

FIG. 6 shows a top view of the separated pilsner container components;

FIG. 7 shows a bottom view of the pilsner container of the invention; and,

FIG. 8 shows a bottom view of the separated pilsner container components.

The broken lines in the drawings represent unclaimed subject matter and form no part of the claimed design.
